CONTROL SYSTEM FOR GYRO VERTICALS

Filed March 7, 1947

3 Sheets-Sheet 1

Diagram illustrating the internal structure and signal flow of a gyroscopic system, likely a gyroscopic compass, showing two gyroscopes (top and bottom) and their associated electronic control and feedback loops.

Top Gyroscopic Assembly:

- Labels 10 through 25 are present, with 10 at the top, 22 near the top center, 18 near the top left, 17 near the top right, 11 near the top center, 16 near the top left, 24 near the top center, 25 near the top right, 12 near the center, 41 near the center, 45 near the center, 20 near the center, 21 near the center, 23 near the center, 13 near the center, 14 near the center, 15 near the top center, and 11 near the top center.

Bottom Gyroscopic Assembly:

- Labels 26 through 38 are present, with 26 near the top, 40 near the top center, 36 near the top left, 32 and 34 near the top right, 33 near the center, 31 near the center, 38 near the center, 39 near the center, 30 and 53 near the center, 56 and 53 near the center, 57 near the center, 54 near the center, 55 near the center, 52 near the center, 118 near the center, 115 near the center, 58 near the center, and 59 near the center.

Central Vertical Column:

- Labels 41 through 58 are present, with 41, 42, 43, 44, 45, 46, 47, 48, 49, 50, 51, 52, 53, 54, 55, 56, 57, 58, and 59 arranged vertically.

Block Diagram (Right Side):

- Labels 118, 115, 120, 102, 101, C, and C' are present, indicating a feedback loop involving capacitors C and C'.
- Block diagram showing signal flow from the gyroscopes through amplifiers, integrators, and differentiators to a final output stage involving capacitors C and C'.

CONTROL SYSTEM FOR GYRO VERTICALS

Spencer Kellogg, 2nd, Glen Head, Robert F. Hays, Jr., Syosset, and Clare E. Barkalow, Huntington, N. Y., assignors to The Sperry Corporation, a corporation of Delaware

Application March 7, 1947, Serial No. 733,250

23 Claims. (Cl. 74—5.34)

1

The present invention relates to a control system for gyro verticals for high speed aircraft. All gyro vertical instruments are subject to certain errors in the reference they provide of the true vertical. With the trend towards higher speeds in aircraft, these errors reach such a magnitude that present gyro vertical instruments do not always provide an accurate attitude reference or representation of the craft relative to its fore and aft and athwartship axes.

The primary object of the present invention is to so improve a gyro vertical that it provides an accurate reference for high speed aircraft, such as modern jet planes flying at speeds approaching and even exceeding that of sound, despite rough air, turns and accelerations of any type during flight. Our improved gyro system also is compensated for wind velocity exceeding any recorded wind velocities.

The basic components of the improved system include a gyro vertical, a gravity reference for the gyro vertical in the form of a gyro compensated pendulum, and a true air speed meter. The system also includes a means for deriving data concerning the heading of the craft and a means for providing signals for the system in accordance with the speed of the wind, the direction of the wind, and the latitude of the craft.

Our improved gyro vertical system is compensated both for the effect of centrifugal force and linear acceleration on the pendulous reference by the employment of a novel gyro compensated pendulum of the type shown in U. S. Patent No. 2,595,268, issued May 6, 1952, to Spencer Kellogg, 2nd, one of the present applicants.

Coriolis acceleration is corrected for at the gyro compensated pendulum of the system.

The gyro vertical is corrected for the effect of the horizontal component of the earth's rotation.

The gyro vertical of the system is further compensated for drift due to the speed of the craft over the curved surface of the earth which is sometimes referred to as the earth's profile correction.

The gyro vertical of the improved system is a non-pendulous instrument, and therefore is not effected by the noted Coriolis, fore and aft or turn accelerations.

Coriolis acceleration as herein defined, is a deflecting force on a pendulum due to the vertical component of the earth's rotation (which is proportional to the sine latitude (sine L) and the instantaneous velocity of the craft over the earth's surface. The effect of such an acceleration on a pendulum (such as utilized in the

2

improved system in which the same provides a gravity reference for the gyro vertical) is to make the pendulum hang with its lower end slightly to the right or left of truly vertical in a plane at right angles to the heading of the craft. In the northern hemisphere, the reference is displaced to the right hand of a person looking in the direction of travel of the craft. The displacement occurs to the left hand when the craft is in the southern hemisphere. One of the objects of the present invention is to compensate the reference of the improved gyro vertical control system for error therein due to horizontal Coriolis acceleration.

Another feature of the invention is provided by the improved means for damping the gyro compensated pendulum with respect to space coordinates, as determined by the gyro vertical.

Still another feature of the invention comprises the means provided herein for effecting operation of the erecting means at the gyro vertical.

A further feature of the invention resides in the means utilized for correcting the gyro vertical for the ground speed of the craft over the curved surface of the earth. To obtain this correction the effect of the velocity of the wind on the craft is taken into consideration.

The invention in another of its aspects relates to novel features of the instrumentalities described herein for achieving the principal objects of the invention and to novel principles employed in those instrumentalities, whether or not these features and principles are used for the said principal objects or in the said field.

A further object of the invention is to provide improved apparatus and instrumentalities embodying novel features and principles, adapted for use in realizing the above objects and also adapted for use in other fields.

Other objects, features and structural details of the invention will be apparent from the following description when read in relation to the accompanying drawings, wherein:

Figs. 1A and 1B show a system embodying the present inventive concepts in which the elements are schematically represented. These views when joined at lines C—C also provide a diagram showing the connections between the elements located on the respective sheets of the drawing;

Fig. 2 is a vector diagram used in connection with the description of Fig. 1B of the invention; and

Fig. 3 is a section view of the gyro compensated pendulum taken on line 3—3, in Fig. 1A.

With reference to Fig. 1A of the drawing, a gyro vertical as indicated at 10, is shown to include a casing or housing 11 that is suitably fixed to an aircraft (not shown) whose longitudinal or fore and aft axis is represented by the line 12. The gyro vertical, per se, includes a rotor case or frame 13 whose rotor (not shown) is spun about a substantially vertical axis by suitable means known in the art. As shown, the case 13 is universally supported on casing 11 by a gimbal ring 14 in a conventional manner. The major horizontal axis of support of the rotor case 13 of the gyro vertical as indicated at 15 is preferably parallel to or coincident with the fore and aft or longitudinal axis of the aircraft on which the system is employed. The minor horizontal axis of support of the rotor case of the gyro vertical as indicated at 16 is preferably parallel to or coincident with the pitch or athwartship axis of the aircraft. Rotor case 13 is universally mounted on casing 11 in neutral equilibrium so that there is no error caused therein by acceleration effects due to Coriolis, turning of the craft about its vertical axis or change in speed of the craft. A pickoff 17 of the selsyn type is indicated at the pitch axis 16 of the gyro vertical. As shown, the rotor of pickoff 17 is connected to the case 13 and is energized from a suitable source of alternating current electrical energy as indicated at 18. The stator of pickoff 17 is suitably fixed to the gimbal ring 14 of the gyro vertical. The instrument also includes a pickoff 20 of the selsyn type at the roll axis 15. Pickoff 20 includes a rotor that is connected to the gimbal ring 14 and energized from a suitable source of electrical energy 21. The stator of pickoff 20 is connected to the casing or housing 11 of the gyro vertical. The rotors of pickoffs 17 and 20 are stabilized by the gyro vertical while the stators thereof move with movement of the craft from the reference position about its respective pitch and roll axes. With the craft in its reference position, the pickoffs 17 and 20 produce a null output. When this position is departed from, the pickoffs operate, if so connected, to provide an output whose magnitude depends on the extent of the departure and whose phase depends on the direction of the departure or, if connected to another selsyn to position the axis of an alternating magnetic field in the second selsyn parallel to the rotor in the first selsyn.

The gyro vertical also includes erecting means in the form of torque motors 22 and 23. These motors may have a construction similar to that of a two-phase induction motor with a squirrel cage rotor such as shown in Fig. 7 of U. S. Patent No. 2,392,370 to Esval et al. As hereinafter described, the gyro vertical is compensated for the earth's rotation and for the true ground speed of the craft. As shown, the output of pickoffs 17 and 20 may be fed by way of leads 24 and 25 respectively to control the operation of an automatic pilot or a pitch and roll indicating repeater of conventional construction. It is desired to point out that the hereinbefore described elements of the gyro vertical, per se, which form a part of the improved system are well known in the art.

In accordance with the invention, the gravity reference for the gyro vertical 10 is a device that is herein termed a gyro compensated pendulum which may be physically dissociated from the gyro vertical. This device is indicated generally in the drawing at 26. The reference device 26 includes a casing 27 that is suitably fixed in po-

sition on the craft at a point as near as possible to the craft's center of gravity. This point may or may not be remote from the location of the gyro vertical on the craft. In any event, the gyro vertical and its reference device 26 are to be considered as separate elements of the improved system. As shown in Figs. 1A and 3, device 26 provides a pendulous element 28 that is universally mounted in casing 27 for movement about an axis 30 parallel to the fore and aft axis of the craft and an axis 31 parallel to the athwartship or pitch axis of the craft. In the device 26, the pendulum is formed as a part of a gyro rotor case 32 whose minor horizontal axis in gimbal ring 33 corresponds to axis 31 and whose major horizontal axis corresponds to axis 30. The gyro rotor 34 of device 26 in rotor case 32 may be considered to be mounted on the pendulum to spin about an axis coincident with the athwartship axis 31 of the pendulum. Rotor 34 is driven by a suitable motor at a speed proportional to the true airspeed of the craft on which the system is employed. The stator windings of the motor employed for this purpose are indicated at 35 in Fig. 3.

As shown, the gravity reference device 26 further includes a pickoff 36 of the selsyn type at axis 31 and a pickoff 37 of the selsyn type at axis 30. The stator of pickoff 36 is fixed to the gimbal ring 33 and the rotor of this pickoff is adapted to move with the movement of the case 32 or pendulum 28 about axis 31 as the same is fixedly connected thereto. The stator of roll pickoff 37 is mounted on the casing 27 while the rotor of this pickoff is fixedly connected to the ring 33 to move with the case 32 or pendulum 28 when the same move about the axis 30 parallel to the fore and aft axis of the craft. Device 26 also includes a pair of torque motors indicated at 38 and 40 which may be similar in construction to motors 22 and 23 of the gyro vertical 10. In this instance, motor 38 is adapted to exert a damping torque on the rotor case 32 or pendulum 28 about axis 31 and motor 40 is adapted to perform a similar function about axis 30 of device 26.

The gyro 32 operates to correct the pendulum for errors due to the effect of accelerations both when the craft is turning about its vertical axis or changing speed along its fore and aft axis. When the craft turns about its vertical axis, the centrifugal force on pendulum 28 tending to tip the gimbal ring 33 out of a horizontal plane, i. e., to turn it about axis 30, produces just sufficient torque to precess gyro rotor 34 about a vertical axis at the same rate that the airplane is turning for a predetermined air speed. Viewed from a different standpoint, the tendency of the gyro to precess during a turn is opposed by an equal and opposite centrifugal force acting on the pendulum which would otherwise cause it to swing out to the vertical. With acceleration or deceleration along the fore and aft axis of the craft, the pendulum tends to swing about axis 31. This tendency is resisted by a compensating torque applied to the pendulum due to a correlated change in speed of the gyro rotor 34. In both of the noted conditions, the pendulum 28 of the reference device 26 maintains its average position truly vertical. For a more detailed description of the manner of operation of the gyro compensated pendulum device 26, reference is made to the hereinbefore noted Patent No. 2,595,268 based on the improved gyro compensated pendulum per se.

In accordance with the improved system, the

gyro vertical is slaved to the reference device 26 by comparing the position of the pendulum and the gyro vertical about their fore-and-aft and transverse axes, and applying torques to the gyro vertical upon departure of their proper relationship to erect the gyro vertical. For this purpose the output of the pickoff 36 at axis 31 of the reference, combined with the output of a similar pickoff 17 on the gyro vertical, produces a signal controlling the erection of the gyro vertical. This is represented by the lead 45 between pickoffs 17 and 36 and by lead 41 from pickoff 36 to torque motor 22, operating through amplifier 42. About the other axis lead 46 is shown as connecting pickoffs 20 and 37 and lead 43 from pickoff 37 combined with that of pickoff 20 controls torque motor 23 through amplifier 44. When the rotors of the pickoffs in either system depart from positional agreement, an output is produced to which the proper torque motor at the gyro vertical responds to restore the condition. Device 26 provides a gravity reference to which the gyro vertical is slaved as described. The transmission systems described provide a means for combining the outputs of two pickoffs. The respective torque exerting means or motors 22 and 23 at the gyro vertical may be considered to be responsive to the individual combining means.

As herein shown, the slaving means interconnecting the gyro vertical 10 and reference device 26 may also include two integrating networks as indicated generally at 47 and 48. Network 47 provides a means for integrating the output of the transmission system including pickoffs 36 and 17 by tapping lead 41. The output of network 47 is fed by way of lead 50 to amplifier 42 to supplement the input to motor 22, when a persistent average signal exists indicating a stand-off error due to persistent one way drift of the gyro 10. Motor 22 is consequently responsive to the output of the transmission system including pickoffs 36 and 17 and to the output of the integrating network 47. Network 48 operates in a similar manner to control torque motor 23, the output of the same being supplied to amplifier 44 by way of lead 51. Network 48 is tapped to lead 43 so that the same is energized by the output of the transmission system including pickoffs 37 and 20. As the neutral equilibrium gyro vertical 10 is corrected for earth's rotation and the speed of the craft relative to the earth as hereinafter described the average output of the transmission systems described provides a measure of the residual unbalance of the gyro vertical. These signals are integrated by the networks 47 and 48 and fed the torque motors 22 and 23 for the purpose of substantially cancelling such unbalance of the gyro vertical.

In accordance with the present invention, the system provides for the damping of the gravity reference or pendulum 28 or pendulous case 32 of the gyro compensated pendulum device 26. In this connection, motor 38 at the athwartship axis of device 26 is operated by the output of an amplifier 52 fed from a differentiating network indicated at 53 by way of lead 54. The input to network 53 is obtained from a tapped connection to lead 41 carrying the output of the transmission system including pickoffs 36 and 17. By this arrangement, the rate of change of the combined output signal of pickoffs 36 and 17 may be used to damp the pendulum about its axis 31. Motor 38 provides a means responsive to the output of the differentiating network or means for damping the pendulum 28 or pendulous case 32 about its minor axis of support. The pendulum 28 or

pendulous case 32 of device 26 is damped about axis 30 by means of motor 40, amplifier 55 whose output is supplied the motor and a further differentiating network or means indicated generally at 56 which is connected to amplifier 55 by way of lead 57. Network 56 as shown is tapped to the output lead 43 for the transmission system including pickoffs 37 and 20. In this instance, motor 40 operates responsive to the output of differentiating means 56 to damp the pendulum 28 or pendulous case 32 about its fore and aft axis 30.

In accordance with the invention, means are provided to drive the gyro rotor 34 of the device 26 at a speed proportional to the true airspeed of the craft. As herein illustrated, the motor driving the gyro rotor 34 is operated from the output of an amplifier 58 supplied from a two phase generator 60 that is directly driven by shaft 61 driven at a speed proportional to the true air speed of the craft, which is represented diagrammatically as a true air speed meter device 65, which is well known in the art. As herein shown, device 65 is also connected to drive a 400 cycle generator 70 of the type shown in the patents to Riggs, 2,115,086, dated April 16, 1938 or 2,206,920, dated July 9, 1940, to provide a signal proportional to the true airspeed of the craft. As shown in Fig. 1B, this signal is fed to the primary of transformer 71 by way of lead 72. The secondary of transformer 71 provides a signal that is represented in Fig. 2 by the vector V_s depicting the true air speed of the craft. The direction of vector V_s is along the fore and aft axis 12 of the craft 73 shown in Fig. 2. The athwartship axis of the craft is indicated at 74. Device 65 and generator 70 provide a means for producing a signal in accordance with the true air speed of the craft.

A directional baseline such as North is provided for the system for the determination of the true heading ϕ of the craft by means such as a flux valve compass system (not shown) of the character shown and described in Patent No. 2,383,461 issued August 28, 1945. The output of this compass system is connected as shown in Fig. 1B to the stator of a selsyn signal generator 75 on the shaft 77 connected by way of lead 76. The actual power for rotating shaft 77 is provided by a motor 80 controlled through a power amplifier 81 from the signal supplied by generator 75 to move the shaft 77 to a position that represents the true heading ϕ of the craft. As shown, motor 80 is connected to shaft 77 through suitable gears 81, 82. Correction for magnetic variation of the baseline may be set into the system manually by means of knob 83 which sets the stator of the position repeating receiver 75 by way of gears 84, 85 and shaft 86. Shaft 77 may operate a true heading pointer 87 readable in a suitable compass card (not shown) by way of gears 88, 90 and shaft 91. The shaft 77 also positions the rotor of a resolver of the selsyn type indicated at 92 through gears 93, 94 and shaft 95. The rotor of the resolver 92 receives a signal from a selsyn device 96 which is proportional to the cosine of the latitude of the craft. The rotor of device 96 is connected to latitude setting knob 97 by way of shaft 98. Lead 100 connects the stator of device 96 with the rotor of the resolver 92. The stator of the resolver selsyn has two windings as shown that are spaced 90 electrical degrees apart so that the cosine latitude signal from device 96 is multiplied by the sine and cosine functions of the true heading of the aircraft. These signals are then applied through respective amplifiers 75 and 42 to the torque motors 23 and 22 at the

gyro vertical to completely correct the same for drift about the axes of the gyro due to the horizontal component of the earth's rotation. Lead 101 from one of the windings of the resolver 92 connects with lead 41 to the amplifier 42. Lead 102 from the other of the windings of the resolver 92 connects with lead 43 to the amplifier 44. The combination of the directional reference means, the resolver 92 and device 96 provide a means for producing corrective signals in accordance with the components of the earth's rotation about the fore and aft and athwartship axes of the craft. The horizontal component of the earth's rotation about axis 12 or 15 is corrected by the signal to the torque motor 22 from the described means. The horizontal component of the earth's rotation about axis 16 or 17 is corrected by the signal to torque motor 23 from the described means.

The gyro vertical of the system is also corrected for drift due to the speed of the craft around the earth. This correction is similar in nature to the correction for the horizontal component of the earth's rotation. It is due to rotation of the craft about the center of the earth and is sometimes referred to as a correction for the earth's profile. For accuracy, this correction takes into account the ground speed and track of the craft. The order of magnitude of this correction is about the same in extreme instances as the correction due to the earth's rotation. For example, if the craft is travelling at a speed of 700 miles per hour with a tail wind of 200 miles per hour, the ground speed is 900 miles per hour which is about nine tenths of the speed of the earth at the equator where the earth's rotation correction on the gyro vertical is maximum.

In accordance with the present invention, the drift of the gyro vertical due to the speed of the craft relative to the earth is corrected for by means including a resolver 103 of the type described for resolver 92. In this instance, the double wound part of the resolver is positioned by shaft 95 in accordance with the reference position of shaft 77 thereby taking into account the true heading of the craft. The other part of resolver 103 is set manually by a knob 104 in accordance with wind direction as represented at ϕ_w in Fig. 2. Vector Vw representative of the magnitude of wind velocity is set into the system manually through means of potentiometer 105 whose movable arm 106 is positioned in accordance with the manual setting of knob 107. Potentiometer 105 and resolver 103 are connected by leads 108. Similar to resolver 92, the resolver 103 divides a signal proportional to vector Vw into components one of which is along the fore and aft axis 12 and the other of which is along the athwartship axis 17 of the craft. As represented in Fig. 2, Vw_1 is the component of wind velocity along axis 12 of the craft and Vw_2 is the component of wind velocity along the axis 17 of the craft. The signal proportional to the fore and aft component of wind velocity is fed by lead 108 to the secondary of transformer 71 where it is additively combined in this instance with the signal proportional to V_s . The combined signals are fed by way of lead 110 to lead 101 and thence to torque motor 22 through amplifier 42. The signal proportional to the athwartship component of wind velocity is fed by leads 111, 112 to lead 102 and thence to torque motor 23 through amplifier 44. The corrections thus applied to the gyro vertical in this connection are in accordance with the actual ground track and speed of the craft as respectively indicated by the angle ϕ_g and vector V in Fig. 2.

Amplifier 44 provides a combining means for the athwartship component signals of both earth's rotation correction and the craft's speed correction. Amplifier 42 provides a combining means for the fore and aft component signals of both earth's rotation correction and the craft's speed correction.

The gravity reference of the improved system is corrected for Coriolis acceleration both along the fore-and-aft axis and the athwartship axis of the craft. Means are provided for producing signals in accordance with the component of this acceleration along the fore and aft and athwartship axes of the craft. The signal corresponding to the fore and aft component of Coriolis acceleration, which acts about the athwartship axis, is derived from potentiometer 105, resolver 103, the directional reference, and transformer 71 and is represented by vector V in Fig. 2. This signal is fed to a selsyn device 113 by way of lead 114. Device 113 multiplies the signal by a factor corresponding to the sine of the latitude of the craft's position. The output of device 113 is fed to torque motor 40 by way of amplifier 55 to effect the necessary correction. Lead 115 carries this output.

The signal corresponding to the component of Coriolis acceleration along the athwartship axis (which acts about the fore-and-aft axis) is derived from potentiometer 105, resolver 103 and the directional reference and is represented by vector Vw_2 in Fig. 2. This signal is fed to a selsyn device 116 by way of lead 117 which connects with lead 111. Computing device 116 multiplies the signal by a factor corresponding to the sine of the latitude of the craft's position. The output of device 116 is fed to torque motor 38 by way of amplifier 52 to effect the necessary correction. Lead 118 carries this output. The rotors of devices 113 and 116 are connected to shaft 98 that is positioned manually in accordance with the latitude of the craft.

The vertical component of the earth's rotation also has an effect about the fore and aft axis of the gyro compensated pendulum 26 acting as a rate gyro, but this effect is over-compensated or more than nullified by the effect of the torque about the fore and aft axis produced by the aforementioned Coriolis acceleration acting along the athwartship axis, the latter being substantially double the former and opposite in sign. Therefore, we employ in the output of the Coriolis corrector along the athwartship axis, a halving potentiometer 120, which halves the input from device 113 to the amplifier 55, thus applying a proper correction to the fore and aft axis torque 40 for both effects.

Since many changes could be made in the above construction and many apparently widely different embodiments of this invention could be made without departing from the scope thereof, it is intended that all matter contained in the above description or shown in the accompanying drawings shall be interpreted as illustrative and not in a limiting sense.

What is claimed is:

1. In a control system for aircraft gyro verticals, a gravity reference comprising a gyro compensated pendulum having a pendulum movable about an axis parallel to the athwartship axis of the craft, a gyro rotor mounted on said pendulum for spinning about an axis coincident with the axis of the pendulum, and a pick-off at the axis of said pendulum producing an output operable to erect the gyro vertical upon variation in the

relative vertical positions of said gyro vertical and pendulum.

2. In a control system for aircraft gyro verticals, a gravity reference comprising a gyro compensated pendulum having a pendulum movable about an axis parallel to the fore and aft axis of the craft, a gyro rotor mounted on said pendulum and spinning about a normally horizontal axis parallel to the athwartship axis of the craft, and a pickoff at the axis of said pendulum producing an output operable to erect the gyro vertical upon variation in the relative vertical positions of said gyro vertical and pendulum.

3. In a control system for aircraft gyro verticals, a gravity reference comprising a gyro compensated pendulum having a universally mounted pendulum movable about normally horizontal axes parallel to the athwartship and fore and aft axes of the craft, a gyro rotor mounted on said pendulum and spinning about an axis coincident with the athwartship axis of said pendulum, and a pickoff at the fore and aft axis of said pendulum producing an output and a pickoff at the athwartship axis of said pendulum producing an output, said two outputs being used to erect the gyro vertical.

4. A control system for aircraft gyro verticals including a gyro vertical, a gravity reference for said gyro vertical comprising a gyro compensated pendulum having a universally mounted pendulum movable about axes parallel to the athwartship and fore and aft axes of the craft, a gyro rotor mounted on said pendulum spinning about an axis coincident with the athwartship axis of the pendulum at a speed in accordance with the speed of the craft, a pickoff at the fore and aft axis of the pendulum, a pickoff at the athwartship axis of the pendulum, and erecting means at said gyro vertical responsive to the outputs of said pickoffs.

5. In a control system for aircraft gyro verticals, a gyro vertical having a rotor frame pivotally mounted about an axis parallel to the athwartship axis of the craft, a gravity reference for said gyro vertical comprising a gyro compensated pendulum having a pendulum mounted to move about an axis parallel to the athwartship axis of the craft, a gyro rotor mounted on said pendulum and spinning about an axis coincident with the athwartship axis of the pendulum, a first pickoff at the athwartship axis of the rotor frame of the gyro vertical, a second pickoff at the athwartship axis of the pendulum, a comparator system including said first and second pickoffs, and torque exerting means at the gyro vertical responsive to the output of said comparator system.

6. A system as claimed in claim 5, which includes means for integrating a portion of the output of said comparator system, and said torque exerting means is responsive to the output of the comparator system and the integrating means.

7. In a control system for aircraft gyro verticals, a gyro vertical having a rotor case pivotally mounted about an axis parallel to the fore and aft axis of the craft, a gravity reference for said gyro vertical comprising a gyro compensated pendulum having a pendulum mounted to move about an axis parallel to the fore and aft axis of the craft, a gyro rotor mounted on said pendulum and spinning about a normally horizontal axis parallel to the athwartship axis of the craft, a first pickoff at the fore and aft axis of the rotor case of the gyro vertical, a second pickoff at the

fore and aft axis of the pendulum, a comparator system including said first and second pickoffs, and torque exerting means at the gyro vertical responsive to the output of said comparator system.

8. A system as claimed in claim 6, which includes means for integrating a portion of the output of said comparator system, and said torque exerting means is responsive to the output of the comparator system and the integrating means.

9. In a system of the class described, the combination of a pendulum movable about an axis, a gyro vertical having a rotor frame pivotally mounted about an axis parallel to or coincident with the axis of the pendulum, a pickoff at said gyro vertical and a pick-off at said pendulum, said pick-offs producing a differential output upon relative inclination of said pendulum and gyroscope about said axis, means for differentiating said output and means responsive to the output of said differentiating means for damping said pendulum about said axis.

10. In a system of the class described, the combination of, a pendulum movable about an axis, a first pickoff at said pendulum, a gyro vertical having a rotor case pivotally mounted about an axis parallel to or coincident with the axis of the pendulum, a second pickoff at said gyro vertical, a signal transmission system including said first and second pickoffs and adapted to produce an output proportional to the departure between said pendulum and gyro vertical, means for differentiating the output of said system, and means responsive to the output of said differentiating means for damping said pendulum about its axis.

11. In a system of the class described, the combination of, a pendulum universally supported to move about pitch and roll axes, a gyro vertical having a rotor case universally mounted about pitch and roll axes, a first pickoff at said gyro vertical producing an output with departure of said rotor case from a null position about the roll axis, a second pickoff at said gyro vertical producing an output with departure of said rotor case from a null position about the pitch axis, means for differentiating the output of said first pickoff, and means responsive to the output of said differentiating means for damping said pendulum about its roll axis, means for differentiating the output of said second pickoff, and means responsive to the output of said differentiating means for damping said pendulum about its pitch axis.

12. In a system of the class described, the combination of, a pendulum universally supported to move about pitch and roll axes, a first pickoff at said pendulum producing an output with movement of said pendulum from a reference position about its roll axis, a second pickoff at said pendulum producing an output with movement of said pendulum from a reference position about its pitch axis, a gyro vertical having a rotor case universally mounted about pitch and roll axes, a third pickoff at said gyro vertical producing an output with departure of said rotor case from a null position about the roll axis, a fourth pickoff at said gyro vertical producing an output with departure of said rotor case from a null position about the pitch axis, a first signal comparator system including said first and third pickoffs, means for differentiating the output of said system, means responsive to the output of said differentiating means for damping said pendulum about its roll axis, a second signal comparator system including said second and fourth pick-

offs, means for differentiating the output of said second system, and means responsive to the output of said differentiating means for damping said pendulum about its pitch axis.

13. In a system of the class described, the combination of, a gyro compensated pendulum including a pendulous gyro rotor case movable about an axis and a gyro rotor supported by said case for spinning about an axis coincident with the axis of said case, a gyro vertical having a rotor case pivotally mounted about an axis parallel to the axis of said pendulous case, a signal generating system at said gyro vertical and said gyro pendulum producing an output with departure between said cases from a predetermined relationship about said axis, means for differentiating the output of said system, and means responsive to the output of said differentiating means for damping said pendulous case about its axis.

14. In a system of the class described, the combination of, a gyro compensated pendulum including a pendulous gyro rotor case movable about an axis and a gyro rotor supported by said case spinning about an axis coincident with the axis of said case, a first pickoff at said pendulous case producing an output with movement of said case from a reference position, a gyro vertical having a rotor case pivotally mounted about an axis parallel to the axis of said pendulous case, a second pickoff at said gyro vertical producing an output with departure of said case from a null position about said axis, a signal comparator system including said first and second pickoffs, means for differentiating the output of said system, and means responsive to the output of said differentiating means for damping said pendulous rotor case about its axis.

15. In a control system of the class described, an aircraft gyro vertical having a rotor case supported in neutral equilibrium on an axis parallel to the athwartship axis of the craft, means for exerting a torque about the athwartship axis of the case, first means including a compass and a resolver for producing a signal in accordance with the component of the earth's rotation along the athwartship axis of the craft, second means also including said compass and a resolver for producing a signal in accordance with the component of wind velocity along the athwartship axes of the craft, and means for combining the signals of said first and second producing means to operate said torque exerting means.

16. In a control system of the class described, an aircraft gyro vertical having a rotor case supported in neutral equilibrium on an axis parallel to the fore and aft axis of the craft, means for exerting a torque about the fore and aft axis of the case, first means including a compass and a resolver for producing a signal in accordance with the component of the earth's rotation along the athwartship axis of the craft, second means including a wind velocity and wind direction set and an airspeed meter for producing a signal in accordance with the fore-and-aft component of the ground speed of the craft, and means for combining the signal of said first and second producing means to operate said torque exerting means.

17. In a control system of the class described, an aircraft gyro vertical having a rotor case supported in neutral equilibrium on an axis parallel to the fore and aft axis of the craft and an axis parallel to the athwartship axis of the craft, means for exerting a torque about the fore and

aft axis of the case, means for producing a signal in accordance with the ground speed of the craft for operating said fore and aft torque exerting means, means for exerting a torque about the athwartship axis of the case, and means for producing a signal in accordance with the component of wind velocity along the athwartship axis of the craft for operating said athwartship torque exerting means.

18. In a system of the class described, a gravity reference for an aircraft gyro vertical comprising a gyro compensated pendulum having a pendulum with an axis parallel to the athwartship axis of the craft, a gyro rotor mounted on said pendulum spinning about an axis coincident with the axis of the pendulum, means for exerting a torque about the athwartship axis of the pendulum, and means for producing a signal in accordance with the component of Coriolis acceleration along the fore and aft axis of the craft to operate said torque exerting means.

19. In a system of the class described, a gravity reference for an aircraft gyro vertical comprising a gyro compensated pendulum having a pendulum with an axis parallel to the fore and aft axis of the craft, a gyro rotor mounted on said pendulum spinning about an axis parallel to the athwartship axis of the craft, means for exerting a torque about the fore and aft axis of the pendulum, and means for producing a signal in accordance with the component of Coriolis acceleration along the athwartship axis of the craft to operate said torque exerting means.

20. A gyro compensated pendulum, as claimed in claim 19, in which the last-named signal is halved because of the partial correction for Coriolis error due to the vertical component of the earth's rotation about the fore-and-aft axis of the craft.

21. In a control system of the class described, an aircraft gyro vertical having a rotor frame supported in neutral equilibrium on an axis parallel to the fore and aft axis of the craft, means for exerting a torque about an axis of said frame, first means for producing a signal in accordance with the true air speed of the craft, second means for producing a signal in accordance with the component of wind velocity along the fore and aft axis of the craft, and means for combining the signals of said first and second producing means to operate said torque exerting means.

22. The combination of a pendulum mounted on a moving craft with an axis of freedom parallel to the fore and aft axis of the craft, means for exerting a torque about said axis of the pendulum, means for producing a signal in accordance with the component of Coriolis acceleration along the fore and aft axis of the craft, means for halving the signal of said signal producing means, and means for operating said torque exerting means by the signal output of said halving means for correcting the pendulum for the effect thereon of the vertical component of the earth's rotation and of said Coriolis acceleration.

23. In a control system of the class described, an aircraft gyro vertical having a rotor case supported in neutral equilibrium on axes parallel to the fore-and-aft and athwartship axes of the craft, means for exerting a corrective torque about the athwartship axis of the case to compensate for the drift of the gyro due to the earth's rotation and to the craft's velocity thereover, first means including a compass, a magnetic variation corrector and a resolver for pro-

ducing a signal proportional to the component of the earth's rotation along the fore-and-aft axis of the craft, second means for producing a signal proportional to the true airspeed of the craft, third means also including said compass and resolver for producing a signal proportional to the component of the wind velocity along the fore-and-aft axis of the craft, and means for combining the signals of said first, second and third producing means to operate said torque exerting means.

SPENCER KELLOGG, 2ND.
